Primary Examiner — Terry A Wallace

(57) **CLAIM**

The ornamental design for a pizza spatula as shown and described.

DESCRIPTION

FIG. 1 is a front, right, and bottom perspective view of the first embodiment of a pizza spatula, showing my new design;

FIG. 2 is rear, left, and top perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front, left, and bottom perspective view of the second embodiment of the pizza spatula;

FIG. 10 is front, left, and top perspective view thereof;

FIG. 11 is a front view thereof;

FIG. 12 is a rear view thereof;

FIG. 13 is a left view thereof;

FIG. 14 is a right view thereof;

FIG. 15 is a top view thereof;

FIG. 16 is a bottom view thereof; and,

FIG. 17 is a detailed view taken from the encircled portion labeled "17" in FIG. 13.

The short-dash and long-dash broken lines in FIGS. 13 and 17 denote the boundaries of the detail areas and form no part of the claimed design. The even broken lines in the drawings depict portions of the pizza spatula and form no part of the claimed design.

1 Claim, 17 Drawing Sheets
